UNITED STATES PATENT OFFICE.

SIEGFRIED SCHEFFLER, OF ROSTOCK, MECKLENBURG, GERMANY.

BLOWER.

Application filed August 30, 1921. Serial No. 497,053.

(GRANTED UNDER THE PROVISIONS OF THE ACT OF MARCH 3, 1921, 41 STAT. L., 1313.)

To all whom it may concern:

Be it known that I, SIEGFRIED SCHEFFLER, citizen of Germany, residing at Rostock, Mecklenburg, Germany, have invented certain new and useful Improvements in Blowers (for which I have filed an application in Germany Oct. 4, 1919), of which the following is a specification.

The present invention refers to an apparatus for producing jets of air at any desired temperature; preferably heated to a certain degree, for medical particularly dental purposes, for instance for the treatment of diseases of the teeth, oral affections, wounds in the oral cavities or diseases of the throat or nose and open wounds of all description for the purpose of creating a healing action by blowing air of a given temperature against the affected parts, eventually at the same time introducing into the air medicines, drugs and the like.

The new apparatus consists mainly of a fixed or floating casing through which an air pipe projects, combined with a regulatable heating device and means for indicating the temperature, and may also be combined with means for introducing medicine into the air passing through the tube, which means preferably are arranged on the feeding end of the apparatus.

The different constructive elements are known per se, but are new in the particular combination used for the purpose stated above. The apparatus can also be employed for other purposes than those stated, for instance for making cavities of a tooth dry before filling them, or when bridges or plates and the like are to be attached. In constructing the apparatus another object has been taken into account, and that is to enable the physician or dentist to operate without any assistants, even in such cases where other means, generally found in dentist shops, are not at his disposal.

In the drawing Fig. 1 is a longitudinal section of the apparatus shown independently of any supports.

Fig. 2 is the end view of the apparatus shown in Fig. 1.

Fig. 3 is an elevation of the apparatus supported on the usual dentist's floating table.

Figs. 4 and 5 show modifications of a spout used on the apparatus, and

Fig. 6 is a longitudinal section of a modification of the apparatus shown in Fig. 1.

Fig. 7 is an elevation partly in section of a larger plant, in which the apparatus is used, combined with means for producing steam.

Fig. 8 is a longitudinal section of a spout used in the apparatus shown in Fig. 7.

Fig. 9 is an elevation, and

Fig. 10 a plan of a modification of the apparatus shown in Fig. 7, adapted to be used as a portable table apparatus.

Fig. 11 is an elevation of another modification of the apparatus shown in Fig. 7, adapted to be supported on a roller, and

Fig. 12 is an elevation of a tube which can be used together with the apparatus shown in Fig. 11.

The apparatus particularly shown in Figs. 1 and 2 consists of a casing *a*, preferably of cylindrical or oval cross section, through which an air feed pipe *b* projects. Within the casing *a* a heating device *c* is arranged below the pipe *b*. In the construction shown the heating device consists of a gas pipe *c*, running throughout the length of the casing *a*, and having a number of gas jets *d* to heat the pipe *b* from below. By the cock *e* in the pipe *c* the gas nozzle can be regulated at will. Also the air feed pipe *b* is provided with a cock or valve *f* for throttling the air passing through it.

In front of the casing *a* the pipe *b* is provided with a thermometer *g*, by the aid of which the temperature of the air driven through the pipe *b* can be read off. Thus not only the desired amount of air passing the pipe but also its temperature can be regulated at will according to the object aimed at or according to the sensitiveness of the patient.

On the front end of the pipe *a* a spout *h* can be slipped, which may have any suitable construction. In Figs. 1, 4 and 5 three constructions are shown by way of example.

The apparatus as described above can be supported or attached in any suitable manner, either fixed or floating to enable the apparatus to be held in any desired position as requirements may suggest. In the form shown in Figs. 1 and 2 the casing *a* is pivoted to a yoke *i* rotatably supported on an arm *k*, which may be rotatably attached to a support *k* by a clamping screw *k*.

In the modification shown in Fig. 3 the

apparatus is attached by articulated arms to a floating table *m* usually made use of by dentists. If desired the apparatus may be suspended from the ceiling, the suspending cord passing for instance over a roller *j* (Fig. 11) as is usual in suspending lamps to enable the apparatus to be held in any desired floating position. It is of importance that the apparatus can be adjusted by 5 hand into the desired position and then left to itself, without necessitating the physician's holding the apparatus, so that his hands are perfectly free when carrying out any desired operation in treating the 10 affected parts of the patient. According to need the spout shown in Fig. 1 can be replaced by any other construction, for instance such as shown in Figs. 4 and 5. In Fig. 5 the spout is supposed to be flexible. 15 The thermometer *g* may either be fixed as shown in Fig. 1 or removable as shown in Fig. 6. By the aid of this thermometer at any time the degree of heat of the air, passing from the apparatus, can be determined. 20 By adjusting the cock *e*, the temperature may be raised or lowered, and by adjusting the cock *f* the amount or speed of air can be regulated.

Preferably in the neighbourhood of the 30 thermometer, for instance behind the thermometer on the hot air tube *b*, a device can be attached for introducing an antiseptic or other medicine into the stream of air. In the modification shown in Fig. 6 this 35 device consists of a funnel like vessel or hopper *q* which, by a conical part, opens out into the tube *b*. That part of the tube *b* below the hopper *q* may be filled up with a sponge or a sucking-wick or other absorbent 40 *t*, so as to distribute the medicine flowing out of the hopper and to enable the medicine to be easily vaporized by the hot air passing through the absorbent. If desired, a dropping device *r* may be provided for allowing 45 the medicine to pass out from the hopper by drops. To hold the absorbent at its place on one or both sides a wire-netting *s* may be fitted into the tube *b*, thus improving 50 the distribution of the absorbent throughout the cross section of the tube *b*. The front wire-netting prevents the liquid from being drawn along with the air unevaporated. By this means not only warm 55 air but also a medicine or antiseptic drug may be introduced into the air to treat wounds or other affected parts of the body.

The heating device formed by the tube may be removable, to enable this device to be interchanged by some heating means, for 60 instance an electric heating device *c* as shown in Fig. 11.

If a gas or spirit burner is used, it is advisable to protect or strengthen the tube *b* by a mantle *n*, partly surrounding the 65 tube on its lower side.

The air used for the burner may enter the casing *a* by the lower openings *o*, and the products of combustion may escape by the upper openings *p*. By an opening *r* (Fig. 2) of the cover *a* of the casing *a* the 70 gas may be ignited.

If desired the apparatus described above may be combined with means to enable it to give off steam. In this case the apparatus is connected or combined with a small 75 boiler of any desired description. The apparatus shown in Fig. 7 is well adapted for this purpose. The tube *b* in this apparatus is not only connected with an air blower *u* by the pipes *u*¹ and *u*², but also with a boiler 80 *v* by the pipe *u*³. The boiler *v* may be heated by electricity, for instance by resistance wires *v*, which according to need may be shunted off by a switch *v*². The steam created in the boiler will pass through the 85 pipe *u*³ into the pipe *b* and mingle with the air introduced into the pipe *b* by the pipe *u*². If it is found that this mixture of air and steam is sufficiently hot, the cock *e* for the heating device *c* within the casing *a* may be 90 closed. But when it is desired to superheat the steam or the mixture of steam and air, the heating device *c* may be ignited. By the valves or cocks *u*⁴ *u*⁵ the mixture 95 of air and steam may be regulated in any desired manner.

The boiler *v* described above might also be used for introducing a spray of cold water into the air driven through the tube *b* by the blower *u*. In this case the tube *u*¹ 100 may be connected with the boiler *v* by an other tube *u*⁶ passing into the boiler and reaching into the water. If desired the lower part *u*⁷ of this tube may be perforated, and in order to increase the length of this 105 part of the tube it may be shaped helically as shown in Fig. 7. By these means, when the electric heater *v*¹ is shunted off, a spray 110 of water will be created when the cocks *u*⁸ and *u*⁹ are opened, thus mixing the air 115 driven by the blower *u* through the apparatus with a spray of cold air, which mixture may be heated at any desired degree by the heater *c*.

The spout *h*¹ may be so constructed as to 116 allow atmospheric air to be drawn along with the jet produced by the apparatus. For this purpose the tube *h* is provided with a nozzle *h*¹, and at the rear end of the spout *h*¹ there is a hit and miss valve consisting 120 of a ring *h*² provided with openings *h*⁴ which correspond to openings *h*³ at the rear end of the spout *h*¹ (Fig. 8). Thus by rotating the ring *h*², the openings *h*³ may be closed or opened more or less to regulate the amount of atmospheric air mixing with the jet produced by the apparatus.

In the modification shown in Fig. 8, the medicine hopper *q* is connected with a thin helical pipe *q*¹ through which the medicine 130

or drugs are heated and evaporized by the heat of the jet passing through the nozzle b^1 .

The boiler v may also be provided with a thermometer g^1 for enabling a regulation of the heat of steam produced in the boiler.

In Figs. 9 and 10 another modification is shown in which the boiler v and the apparatus a, b is arranged within a common casing a^2 . The same letters of reference as used in Fig. 7 are also used in Figs. 9 and 10 to indicate similar parts. The modification (Figs. 9 and 10) is portable and intended particularly for dentists or physicians for throat and nose, while the apparatus shown in Fig. 7 is well adapted for large hospitals. In both cases hot air either mixed with medicated vapour or steam or cold spray may be applied according to need.

In the modification shown in Figs. 9 and 10 a special tube u^3 is employed to connect the boiler directly with the pipe b after leaving the casing a so as to enable steam to enter the spout h directly if desired.

The modification shown in Fig. 11 is particularly well adapted for dentists or other physicians, particularly for specialists for the nose and mouth. In this modification a boiler v^2 is connected with the casing a constituting the apparatus shown in Fig. 1 in such manner that the complete apparatus can be suspended from the ceiling for instance over a roller j . Similar letters of reference indicate similar parts such as shown in Figs. 7, 9 and 10.

If this floating apparatus is used for dentists, the pipe b can be connected with any spout h or h^1 shown in Figs. 1, 4, 5 and 8, or it can be connected with a flexible tube h^4 provided at its end with an inhaling mask h^5 or with a flexible tube h^6 provided at its end with a nose piece h^7 . Thus this apparatus can be used for any desired purposes.

I claim:

1. An apparatus for producing jets of air and steam for medical purposes comprising a casing, an air pipe passing through the casing, a heating device within the casing below the air pipe, a thermometer projecting into the air pipe, a blower connected with and adapted to drive air through the air pipe, a steam boiler, pipes connecting both blower and boiler to the air pipe, valves in the connecting pipes to regulate the flow of

air and steam, a third pipe connecting the blower directly with the boiler and projecting into the water of the boiler.

2. An apparatus for producing jets of air or steam for medical purposes comprising a casing, an air pipe passing through the casing, a heating device within the casing below the air pipe, a thermometer projecting into the air pipe, a blower connected with and adapted to drive air through the air pipe, a steam boiler, pipes connecting both blower and boiler to the air pipe, valves in the connecting pipes to regulate the flow of air and steam, a third pipe connecting the blower directly with the boiler and having a perforated portion projecting into the water of the boiler.

3. An apparatus for producing jets of air or steam for medical purposes, comprising a casing, an air pipe passing through the casing, a heating device within the casing below the air pipe, a thermometer projecting into the air pipe, means for introducing a medicine into the air tube consisting of a hopper opening into the air pipe from above, a thin pipe forming a prolongation of the hopper and running along within the air pipe adapted to vaporize the medicine coming from the hopper by the heated air or steam passing through the air pipe, means for regulating the stream of air passing through the air pipe, and means for regulating the heating device.

4. An apparatus for producing jets of air or steam for medical purposes, comprising a casing, an air pipe passing through the casing, a heating device within the casing below the air pipe, a thermometer projecting into the air pipe, means for introducing a medicine into the air tube consisting of a hopper opening into the air pipe from above, a thin pipe forming a prolongation of the hopper, and bent to form a helice, and running along within the air pipe adapted to vaporize the medicine coming from the hopper by the heated air or steam passing through the air pipe, means for regulating the stream of air passing through the air pipe, and means for regulating the heating device.
